(57) **CLAIM**

The ornamental design for a griddle, as shown and described.

DESCRIPTION

FIG. 1 is a top, front and right side perspective view of a griddle in accordance with a first embodiment of my new design;

FIG. 2 is a bottom, rear and left side perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof;

FIG. 9 is a top, front and right side perspective view of the griddle in accordance with a second embodiment of my new design;

FIG. 10 is a bottom, rear and left side perspective view of the second embodiment;

FIG. 11 is a front elevation view of the second embodiment;

FIG. 12 is a rear elevation view of the second embodiment;

FIG. 13 is a left side elevation view of the second embodiment;

FIG. 14 is a right side elevation view of the second embodiment;

FIG. 15 is a top plan view of the second embodiment; and,

FIG. 16 is a bottom plan view of the second embodiment.
